Assistant Examiner — L. Martinez-Rivera

(57) **CLAIM**

The ornamental design for a combined display apparatus and jewelry item, as shown and described.

DESCRIPTION

FIG. 1 is a front perspective view of a combined display apparatus and jewelry item showing our new design;

FIG. 2 is a front view thereof;

FIG. 3 is a rear view thereof;

FIG. 4 is a rear perspective view thereof;

FIG. 5 is a left-side view thereof, the right-side view being a mirror image thereof; and,

FIG. 6 is a top plan view thereof, the bottom plan view being a mirror image thereof.

The broken lines in the figures represent portions of the combined display apparatus and jewelry item that form no part of the claimed design.

1 Claim, 6 Drawing Sheets
